DESIGN FOR A VELOCIPED

Henry D. Rockwell, Detroit, Mich.

Application March 28, 1946, Serial No. 128,032

Term of patent 3½ years

(Cl. D34—15)

To all whom it may concern:

Be it known that I, Henry D. Rockwell, a citizen of the United States, residing at Detroit, in the county of Wayne and State of Michigan, have invented a new, original, and ornamental Design for a Velocipede, of which the following is a specification, reference being had to the accompanying drawing, forming part thereof.

Fig. 1 is a side elevational view of a velocipede, showing my new design;

Fig. 2 is a top plan view of Fig. 1; and
Fig. 3 is a front end view of Fig. 1.

I claim:

The ornamental design for a velocipede, as shown.

HENRY D. ROCKWELL.
